GATE MECHANISM.

Application filed February 14, 1921. Serial No. 444,872.

Our invention relates particularly, though not exclusively, to gate mechanism provided to be moved into and out of traffic-obstructing position across roadways, streets or sidewalks, as for example at bridges or railroad crossings, and of a type employing counterbalancing means for the gate arm; our primary object being to provide a construction of gate-operating mechanism of the type referred to, wherein the counterbalancing means for the gate arm is enclosed within the so-called gate-post which involves a housing for the gate-operating parts, thereby to avoid the unsightly appearance produced by the location of the counterweight mechanism exteriorly of the post, and permitting of the use of a gate post of such character that it lends itself, to a high degree, to its provision in the desired ornamental form. Other objects are to provide a comparatively simple and economical construction of gate mechanism and one which will function in a highly desirable manner.

Referring to the accompanying drawings: Figure 1 is a view in front elevation of a gate apparatus constructed in accordance with our invention, the gate arm, which is shown in traffic-obstructing position, being broken away. Figure 2 is a similar view taken at a right angle to the view in Fig. 1, and viewing the mechanism from the right in the last-referred-to figure, certain parts of the structure shown being sectioned. Figure 3 is a plan view of the structure of Figs. 1 and 2, the upper portion of the casing being sectioned. Figure 4 is a broken view in sectional elevation of a detail of the shaft and its support on which the counterbalancing device for the arm is hung. Figure 5 is a perspective view of the main portion of the counterweight employed; and Figure 6, a similar view of one of a plurality of supplemental sections of the counterweight.

As is usual in structures of this general character, the structure involves a so-called gate post represented at 7 and a gate-arm represented at 8.

The gate-post 7 is formed of a housing or casing 9 which may be of any desirable form, in the upper portion of which a shaft 10 is journaled in bearings 11 in opposed side walls of the casing. The shaft 10 has rigidly connected therewith at its ends, which extend exteriorly of the casing, the end portions 12 of the gate arm which, in

accordance with common practice, may be of the type formed of a framework presenting at one end the end portions 12 referred to and tapering toward its opposite end to a very narrow width, though it will be readily understood that the invention is applicable to a gate arm of any form having either a double connection with the shaft as shown in the drawings and hereinbefore referred to, or a single connection only therewith, the gate arm as provided being adapted to be swung from substantially horizontal position shown in Fig. 1, to substantially vertical position.

The shaft 10 at the portion thereof within the casing 9 is provided toward its opposite ends with levers 13 and 14 rigidly connected therewith, the lever 14 having an extension 15 projecting beyond the opposite side of the shaft 10, this extension being pivotally connected with the bifurcated portion 16 of a connecting rod 17 which is provided at its lower end with a deflected portion 18 pivotally connected at 19 to a crank 20 fixed on a shaft 21 journaled in a gear housing 22 rigidly secured with bolts 23 to the bottom of the casing 9 within which it is located. The shaft 21 has rigidly connected therewith a worm-wheel 24 meshing with a worm 25 journaled at its shaft ends 26 in the housing 22, one of these shaft ends carrying a worm-wheel 27 meshing with a worm 28 fixed on a shaft 29 journaled in the housing 22 and shown as forming the armature shaft of an electric motor 30 rigidly secured within the casing 9. The gear train thus provided serves as a means through the medium of which the power exerted by the motor 30, is exerted on the crank 20 to actuate the latter for rocking the shaft 10 and consequently the gate arm. In the particular arrangement shown the motor 30 would be a reversible motor for rocking the shaft 10 first in one direction and then in the other, the shaft 21 being moved in each operation, in the particular arrangement shown, throughout substantially 165 degrees. It may be here stated that the provision of the worm gearing as described permits of such wide ratio of movement between the shafts 29 and 21 that an electric motor may be used for operating the gate at the desired slow speed, and the gearing occupy such a small amount of space that it may be readily housed within a relatively small gate-post.

The end of the lever 13 and the end of the lever 14 opposite that at which it is connected with the connecting rod 17, are connected at the pivots 31, with the bifurcated upper ends 32 of connecting rods 33, the lower bifurcated ends 34 of which straddle and are pivotally connected at 35 with links 36, the connection of these rods with these links being between their ends and the links being pivotally connected at 37 with inwardly-extending lugs 38 provided on a wall of the casing 9. The outer ends of the levers 36 and shown as deflected at 39, are pivotally connected at 40 with the lower ends, respectively, of flexible elements 41 such as chains, as shown, or cables, which extend upwardly from these points of connection and are shown as passing over sprockets 42, or if desired pulleys or bushings, journaled on a shaft 43 mounted at its opposite ends in opposed walls of the casing 9, the ends of these chains, opposite those connected with the levers 36, being attached to the ends of a bar 41^a extending transversely through an opening 44 in the main portion of a counterweight 45 located within the casing 9 and supported therein by the chains referred to, the shape of the portion 45 of the counterweight being preferably that illustrated. By preference the counterweight also comprises a plurality of relatively lighter sections represented at 46 and of the same shape as the section 45, the sections 46 being superposed upon each other and upon the section 45 and all of the parts forming the counterweight being connected together as through the medium of four bolts represented at 47 passing through holes 48 in the various counterweight sections.

The manner of holding the sprockets 42 in properly spaced relation on the shaft 43 is represented in Fig. 4, and involves the provision of end sleeves 49 flanged as indicated at 50 to fit flatwise against the sprockets 42, these sleeves being interposed between the sprockets and the adjacent casing walls, and an intermediate sleeve member 51 interposed between the two pulleys.

According to the particular construction shown, the various parts of the apparatus are in the positions they occupy when the gate arm is in substantially horizontal or, in other words, traffic-obstructing position, in which position the counterweight is raised as shown. To raise the gate, the motor 30 is operated in a direction to rotate the shaft 21 in counter-clockwise direction in Fig. 1 with the result of turning the crank 20 in counter-clockwise direction, and through the medium of the connecting rod 17 rocking the shaft 10 in counter-clockwise direction and swinging the gate arm to substantially upright position. The tendency of the counterweight referred to is to rock the levers 36 upwardly in clockwise direction in Fig. 1 and through the medium of the connecting rods 33 exert

a force against the levers 14 tending to rock them upwardly in anti-clockwise direction, the counterweight referred to being preferably of such weight that it will substantially counterbalance the weight of the gate arm 8 thereby to permit of the operation of the gate with the minimum power and permit of its smooth operation. The motor 30 may be controlled in any desirable manner, such as is commonly the practice in the case of gate mechanism, it being common practice to provide in connection with such apparatus, a limit electric switch controlled by the rotation of the shaft 10 and operating when the shaft reaches a certain position in its rotation in either direction, to automatically shut off the current to the motor. As such mechanisms are common and well known it is not deemed necessary to illustrate the same. It may, however, be stated that in the particular arrangement shown the crank 20 in the gate-raising operation would rotate from the position shown in Fig. 1 and in anti-clockwise direction, substantially throughout 165 degrees, and in the gate-lowering operation, involving, in the particular construction shown, the reversing of the motor 30, rotating in the reverse direction to the position shown in Fig. 1.

As is well understood in the art, the leverage exerted by the gate 8 in its movement from substantially horizontal position to substantially vertical position, becomes decreased as it nears its uppermost position, and in order that the force exerted against the gate arm 8, by the counterweight, be rendered substantially proportionate to the varying leverage exerted by the gate arm as stated, we provide between the shaft 10 and the counterweight, the lever connections as shown, it being apparent from the showing that as the gate nears upright position, the counterweight, by reason of the mechanism as stated, exerts a decreasing force tending to lift the gate.

Furthermore, it will be noted, that by reason of the arrangement of the parts as shown, the movement of the gate will be slower at the beginning and the ending of its movements in both directions, than during its intermediate travel, which is a desirable feature in structures of this character.

The casing is shown as provided with removable closures 52 and 53, the former located in a side wall adjacent the counterweight for closing an opening 54 through which certain parts of the mechanism in the casing are accessible, and the latter closing an opening 55 through which the motor and gear mechanism may be introduced into, and withdrawn from, the casing for installation and repair or replacement, if desired, the motor together with the gear mechanism referred to being preferably mounted on a

removable base permitting these mechanisms to be introduced into the casing and removed therefrom, as a unit.

It will be readily understood from the foregoing that by constructing the apparatus in accordance with our invention, the counterweight mechanism is concealed from view, and the gate-post may be provided as a highly ornamental structure.

10 While we have illustrated and described a particular construction embodying our invention, we do not wish to be understood as intending to limit it thereto as the same may be variously modified and altered without departing from the spirit of our invention.

What we claim as new, and desire to secure by Letters Patent, is:

1. In mechanism of the character set forth, the combination of a casing, a gate arm pivotally connected therewith, means for operating said gate arm, a counterweight, a rod operatively connected with said gate arm eccentrically of its pivot, a lever pivotally supported at one end and connected between its ends with said rod, and a connection between said lever at its outer end and said counterweight.

2. In mechanism of the character set

forth, the combination of a casing, a gate 30 arm pivotally connected therewith, means for operating said gate arm, a counterweight, a rod operatively connected with said gate arm eccentrically of its pivot, a 35 pivotally-supported lever to which said rod is connected, flexible means connected with said counterweight, and means over which said flexible means extend, said flexible means being connected at the end thereof opposite that at which it connects with said 40 counterweight with said lever.

3. In mechanism of the character set forth, the combination of a casing, a shaft, a gate arm fixed on said shaft, means for operating said gate arm, a counterweight, a 45 member on said shaft, a rod pivoted to said member, a pivotally-supported lever extending in a direction opposite to said member, a rod pivotally connecting said member and lever, the engagement of said rod with said 50 lever being between the pivotal support thereof and its outer end, a counterweight, a support, and a flexible element extending over said support and connected with said counterweight and the outer end of said 55 lever.

MAX KUSHLAN.
HUGH E. YOUNG.
